UNITED STATES PATENT OFFICE.

JOSEPH M. NOVY, OF ST. LOUIS, MISSOURI.

ROTARY EXPLOSIVE-ENGINE.

1,038,424.

Specification of Letters Patent. Patented Sept. 10, 1912.

Application filed September 5, 1911. Serial No. 647,753.

To all whom it may concern:

Be it known that I, JOSEPH M. Novy, citizen of the United States, residing at St. Louis, State of Missouri, have invented certain new and useful Improvements in Rotary Explosive-Engines, of which the following is a full, clear, and exact description, reference being had to the accompanying drawings, forming a part hereof.

10 My invention has relation to improvements in rotary explosive engines; and it consists in the novel details of construction more fully set forth in the specification and pointed out in the claims.

15 In the drawings, Figure 1 is a front elevation of the engine, with shaft in cross-section and one of the compression cylinders, in longitudinal section and rock-valve in cross-section taken through the inlet end of 20 its passage-way; Fig. 2 is a combined edge view and vertical cross-section on the broken line 2—2 of Fig. 1; Fig. 3 is a longitudinal elevation and sectional detail on the line 3—3 of Fig. 2, showing the blade of the rotary member advanced to correspond with 25 the second position assumed by the rock-valve, or that position which allows the blade to pass; Fig. 4 is an end view of the rock-valve and controlling spring therefor; 30 Fig. 5 is a side view of the valve with its recess turned from the observer; Fig. 6 is a sectional detail showing the rock-valve in its normal position of rest, the plane of section being taken to one side of the recess in 35 the valve and through the inlet end of the passage-way or chamber thereof; Fig. 7 is a section showing the rock-valve in a position corresponding to Fig. 6, the section being taken however, through the recess of 40 the valve, the blade of the rotary member approaching the valve; Fig. 8 is a sectional detail on the order of Fig. 6, but with valve rocked to its full limit; and Fig. 9 is a sectional detail with the valve rocked to its 45 full limit, the section being taken however, through the recess of the valve, and the blade of the rotary member being shown as having passed the valve.

The object of my invention is to construct 50 a rotary explosive engine, the piston of which shall receive a series of impulses in the course of a single revolution, each impulse being identified with the explosion of a fixed charge of gas.

55 A further object is to construct an engine which will be practically devoid of "dead

centers"; one in which the explosion takes place wholly without the cylinder in which the gas is compressed, thereby permitting the use of a leather piston packing in said cylinder, one which is simple in construction, positive in action, requiring no water cooling, and one possessing further and other advantages better apparent from a detailed description of the invention which is 65 as follows:—

Referring to the drawings, A, A', represent the two sections of the outer casing of the engine, being bolted together along an outer flange as well understood in the art, 70 the section A having secured thereto a spider S and the section A' having cast therewith a spider S', the hubs of the respective spiders serving as bearings for the crank-shaft 1, and the arms of the spider S alternating with the cylinders 8 of the compressor pumps distributed about the section A as presently to be seen. The parts thus far described are within the skill of the ordinary mechanic and no further description 75 thereof is necessary.

Cast with the respective casing-sections A, A', and distributed about the outer edges thereof are a series of (four in the present illustration) valve-casings 3 having a slight 80 taper (or cone-shaped) the axes of the casings being parallel to the axis of the crank shaft 1. Each valve-casing 3 is provided with a receiving or intake nozzle or port 4 and an exhaust nozzle or port 5, the nozzle 90 4 having attached thereto a gas supply pipe 6 provided with a check-valve 7, the supply pipes 6 leading from a common source of gas supply (not shown). The exhaust ports 5 discharge into the atmosphere, the intake 95 ports 4 communicating each with the compression cylinder 8 which in the present construction is an open shell screwed to a leg a cast with the valve-casing. The piston 9 of the cylinder is in the present case 100 provided with a leather packing 10, and hinged to each piston is a connecting rod or link 11, the outer ends of the several connecting rods being pivotally secured to the wrist-pin 12 between the crank-disks 13, 13, 105 of the crank-shaft. Connections of this character are well understood in the art and require no further description in this connection. The wrist-pin 12 extends a suitable distance beyond the outer crank disk or that 110 which is farther removed from the motor-casing A, A', said wrist-pin extension car-

rying a tappet roller 14 for a purpose presently to appear.

Since each cylinder and valve mechanism of the series is the same, a description of 5 one will serve to answer for all, and I will accordingly confine the balance of the descriptive portion to a single cylinder. Secured in any mechanical manner about the cylinder 8, and preferably by bolts *b* as 10 shown, is a band 15 to which is secured a stud 16 serving as a pivot for the oscillating rack-quadrant 17, said quadrant operating as a lever whose short arm terminates in a taper or bevel *d* adapted to be struck by 15 the roller tappet 14 with rotation of the shaft 1, and as the said lever-arm is struck, oscillation is imparted to the quadrant through an arc depending on the length of contact of the roller with the short lever 20 arm thereof. The band 15 is provided with a stop lug 18 for arresting the quadrant as the same is returned to its normal position.

Disposed on the inner surface of the outer 25 arc of the quadrant is a rack 19 the teeth of which mesh with a pinion 20 mounted at the end of the spindle 21 of the rotary or rock-valve 22 mounted in the valve-casing 3, said spindle passing through the adjacent 30 head 23 of the casing, the opposite end of the casing being closed by a head or plate 24 provided with a take-up screw 25 engaging the enlarged boss or trunnion 26 formed on the adjacent end of the valve. With any 35 sweep of the quadrant in a given direction, rotation is imparted to the valve 22, the latter being returned to its original position (in which movement it of course drives back the quadrant to its original position) 40 under the action of a coiled spring 27 interposed between the head 23 and a fiber disk 28 adjacent the small end of the valve, one end of the spring being secured to the spindle 21 and the other end to a pin 29 45 passing through the head 23.

Formed in the valve-casing 3 opposite the cylinder 8 is a discharge port 30 which, for a certain position of the valve 22 is in communication with the intake slot or end of 50 a passage or chamber 31 formed in the valve, the discharge end of said passage being at a point removed approximately ninety degrees from the intake when measured around the valve, and at a suitable 55 distance removed therefrom when measured along the length of the valve. The discharge end of the valve-passage is controlled by a spring check-valve *v* of any approved type, which discharge end is positioned rearward of the basal wall of the recess *R* formed in the wide portion of the valve and located in the casing *A', A'*.

Mounted in the engine casing *A', A'*, and keyed to the shaft 1 is a rotatable member 60 or piston composed of a series of flat blades

32 (set at an incline as in a fan wheel to keep the casing cool) radiating from a central hub and terminating in a rim 33, said rim 33 forming with the inner walls of the casing an explosion chamber 34 which is 70 traversed by a blade 35 radiating from the rim 33, the recess *R* being formed in the valve 22 for the passage of the said blade, the valve being progressively turned so as to cause the outer edge of the blade to clear 75 the basal wall of the recess, the curvature of which wall is substantially in conformity with the arc described by the free edge of the blade. The advancing face of the blade is connected by a stiffening rib 36 having a 80 curved edge, which rib besides serving as a stiffener may perform another function as presently to be seen from a description of the operation of the engine which is as follows:

Confining our attention to a single cylinder 8 (because all the cylinders are alike) and assuming that the crank-shaft 1 and the member 32, 33, keyed thereto, are given a turn contrary to the hands of a watch, it 90 will be seen that the rotation of the crank-disks 13 will impart a reciprocation to the piston 9. Directing our attention to the cylinder shown in section Fig. 1, and supplementing said figure with the illustrations 95 shown in Figs. 6, 7, 8, 9, it will be seen that with an upstroke of the piston, the explosive mixture will be drawn into the cylinder through port 4, and with a downstroke the charge will be compressed within the cylinder (the check-valve 7 preventing a return of the mixture through the pipe 6). The compression of the charge will continue until the tappet roller is on the point of striking or engaging the bevel end *d* of the 100 short lever arm of the rack quadrant 17 by which time the piston has not yet reached its full downward or compression stroke. By the time the tappet roller has traversed what little arc remains to bring the piston 105 to its full stroke, said tappet will have oscillated the quadrant 17 through an arc sufficient to rock the valve 22 ninety degrees, that is to say to a position to bring the base 110 of the recess *R* of the valve in continuity with the outer bounding wall of the annular chamber 34 (Figs. 1, 2, 3). This turn of the valve 22 allows the blade 35 which was approaching the valve to pass through or across the valve (dotted position Fig. 1). By the time the tappet is ready to leave the bevel *d* it will have imparted a further rotation to the valve in the same direction by which time however the blade 35 120 will be on the opposite side of the valve, leaving between it and the blade a chamber 34' (Fig. 9) into which the explosive mixture is discharged (as presently to appear) and where it is exploded. At the moment when the tappet 14 is about to trip the 125

130

Mounted in the engine casing *A', A'*, and keyed to the shaft 1 is a rotatable member or piston composed of a series of flat blades

quadrant 17 the gas has been compressed to a very small compass within the cylinder, but at that moment the port 30 and the passage 31 of the valve are still out of register, the valve not having as yet been moved or rocked from its normal position (Fig. 6). While in its normal position, the valve-controlled discharge end of the passage 31 is just within the chamber 34 (Fig. 7); but 10 the moment the valve is rocked by the incipient oscillation of the quadrant the valve *v* passes out of the chamber 14 behind the valve-casing wall which thus prevents the valve from being unseated, and as the intake end of the passage or chamber 31 comes opposite the port 30, the highly compressed charge of gas is driven into the chamber of the valve whence it can not escape until released into the chamber 34' by the return 20 of the valve to its normal position. Once the compressed charge is thus confined or occluded in the valve chamber 31 it remains there until released. This release is effected as follows:—It will be remembered that by 25 the time the tappet 14 passes off the bevel *d* of the quadrant, the blade 35 will leave between it and the valve a chamber 34' (Fig. 9). During the rocking of the valve to allow the blade 35 to pass, the spring 27 is 30 wound up, so that the moment the quadrant is released from the tappet 14, the spring is not only free to rock the valve back to its normal position, but the valve being geared up to the quadrant as described, the quadrant will likewise oscillate back to its original position (being arrested by the lug 18). The spring 27 being a strong one, the return of the parts to normal 35 position is practically instantaneous; but with the valve 22 rocked back to normal position, the base of its recess *R* is substantially at right angles to the arc of rotation of the blade 35 so that the solid portion of the valve behind or opposite to the recess, 40 faces the chamber 34', and the gases released into said chamber are thus confined on all sides so that they can not escape. Obviously, the gases confined under great 45 tension in the valve-chamber 31 will instantaneously escape past the check-valve *v* into the chamber 34' the moment the valve is thus returned to its original or normal position, in which position the check-valve *v* will emerge from behind the casing wall in 50 which the section of the valve behind the recess is housed, it being understood that the entire periphery of that end of the valve not recessed (the narrow end containing the intake to the passage 31) is entirely 55 surrounded by the metal of its casing 3. By the time the charge of gas is thus delivered to the chamber (or pocket) 34' the charge is exploded and the blade 35 thereby receives an impulse thus imparting rotation to the shaft 1.

There being four cylinders, it follows that the blade of the rotary member will receive four impulses with each revolution, the spent gases escaping through the exhaust ports 5. I have shown a socket *m* 70 for the spark plug, but do not show the plug nor the electric wires, nor the means for closing the circuit at the proper moment, such devices being well known in the art, and it falling within the purview of a 75 skilled mechanic to attach them. I do not of course wish to be limited to any number of cylinders.

It will be seen that the explosion taking place wholly without the cylinder, no injury can befall the leather piston packing and I can thus maintain a perfect piston joint. The vanes or ribs 32 act as fan blades and thus keep the engine cool, while the entire rotary member 32, 33, acts as a 85 fly-wheel for the shaft 1. The engine may of course be started by hand after which it will propel itself.

It is of course true that in order to permit the compressed charge occluded within the valve-chamber 31 to discharge into the chamber 34', the outlet end of said passage controlled by the check-valve *v* must be presented to said chamber, and to do this, the intake end of the passage 31 must pass the 90 port 30, during which interval it might be supposed that the charge would pass back into the cylinder, but it must be noted that at this moment the piston is rising (by "rising" is meant the intake stroke of the 95 piston) and drawing in gas through the port 4 for the next charge. It follows therefore that with gas in the cylinder, the charge compressed within the valve 22 will escape along the line of least resistance 100 which will be into the empty chamber 34'. 105

In the event the member 17 should break while the machine was running, then the curved rib 36 would engage the edge of the base of the valve recess *R*, and turn the 110 valve to accord the blade free passage past it. This is a special function subserved by the rib 36, serving as it does as an emergency member to actuate the valve should the rack and pinion device be put out of 115 commission.

Features illustrated but not alluded to are well understood and require no detailed description.

Having described my invention, what I claim is:—

1. In a rotary explosive engine, a casing, a rotatable member within the same forming an annular chamber with the casing walls, a blade on the rotatable member traversing 125 said chamber, a compression cylinder having a reciprocating piston actuated by the rotatable member, a chambered rock-valve interposed between the discharge from the cylinder and the annular chamber afore- 130

- said, means interposed between the rock-valve and rotatable member for actuating the valve to proper position to cause the chamber thereof to receive the contents from 5 the cylinder, means for permitting the confinement of the charge within the valve-chamber for a definite arc of travel of the blade, and means for effecting a release of the confined charge into the annular chamber 10 behind the blade preparatory to exploding the same.
2. In a rotary explosive engine, a casing; a rotatable member within the same forming an annular chamber with the casing 15 walls, a blade on the rotatable member traversing said chamber, a cylinder having a piston actuated in response to the rotation of the rotatable member, a chambered rock-valve interposed between the discharge 20 from the cylinder and annular chamber and rotating in response to the rotation of the rotatable member to a position to present the passage of the valve to proper position to receive the charge expelled from the cylinder, means for permitting the confinement 25 of said charge within the valve-passage for a definite arc of travel of the blade, and
- means for effecting a release of the confined charge into the annular chamber behind the blade preparatory to exploding the same.
3. In a rotary explosive engine, a casing, a rotatable member within the same forming an annular chamber with the casing walls, a blade on the rotatable member 35 traversing said chamber, a compression cylinder having a piston actuated by the rotatable member, a chambered rock-valve interposed between the discharge from the cylinder and the chamber, means for rotating 40 the valve and its chamber to receive the contents from the cylinder, means for permitting the confining of the charge within the valve-chamber for a definite arc of travel of the blade, and means for effecting the release of the confined charge into the annular 45 chamber behind the blade preparatory to exploding the same.

In testimony whereof I affix my signature, in presence of two witnesses.

JOSEPH M. NOVY.
